UNITED STATES PATENT OFFICE.

CHARLES G. RICHARDSON, OF SPRINGFIELD, VERMONT.

MACHINE FOR APPLYING TRANSFER-STAMPS.

1,086,400.

Specification of Letters Patent. Patented Feb. 10, 1914.

Application filed February 9, 1911. Serial No. 607,647.

To all whom it may concern:

Be it known that I, CHARLES G. RICHARDSON, citizen of the United States, and resident of Springfield, Vermont, have invented certain new and useful Improvements in Machines for Applying Transfer-Stamps, of which the following is a specification.

The present invention relates to the art of applying transfer stamps commonly known as decalcomania stamps to pieces of fabric or such articles as it is desired to mark with said stamps.

While the machine disclosed herein is capable of use for marking a continuous web of fabric, it is also intended to be used for automatically stamping separate articles, such as pieces of underclothing, hosiery, neckties or any other articles to which said stamps may be applied. In its general features it comprises transfer mechanism embracing coöperating pressing members, one of which is heated to effect the transfer of the stamps to the fabric and devices for presenting a series of transfer stamps in proper relationship to the articles to be marked and to the transfer mechanism in order to effect the purpose of the machine.

In the drawings I have illustrated a preferred form of embodying the principles of this invention.

In the drawings Figure 1 is a side elevation of a complete machine ready for service. Fig. 2 is a front end elevation thereof as viewed from the position where the operator stands to feed the articles into the machine. Fig. 3 is a side elevation principally in central section on an enlarged scale. Fig. 4 is a rear elevation of the machine viewed from the end opposite from the feed-in end, that is viewed from the left of Fig. 1. Fig. 5 is a detail view of the main operating lever and its actuating cam. Fig. 6 is a plan view showing part of the tape feeding and the plunger actuating mechanism. Figs. 7, 8 and 9 are detail views in elevation showing the actuating mechanism for lifting the lower presser plate or transfer member and the adjustment therefor. Fig. 10 is a detail view showing the drive for the tape feed rolls.

According to the form illustrated in the accompanying drawings, the machine comprises, generally speaking, a feed apron which carries the articles to be stamped into proper relationship between the two presser or transfer members and mechanism for successively presenting in proper relation-

ship to the series of articles to be stamped, a series of transfer stamps so that when the pressers are actuated the heat of one presser 60 serves to transfer the stamp to a predetermined portion of the article presented. To accomplish the proper evolutions there are, generally speaking, three sets of mechanism which may be termed respectively the 65 stamp feeding mechanism, the mechanism for actuating the transfer members and the mechanism for feeding the articles to the transfer mechanism. In the present embodiment of the invention these three sets 70 of mechanism are all actuated and controlled from a single main actuating lever. In practice I employ a power shaft a which by means of gears a' , a'' serves to drive the main actuating shaft a^3 of the machine. 75 On this main actuating shaft is fixed a properly shaped cam a^4 which engages a bowl a^5 carried by the main actuating lever a^6 from which is derived all the movements of the machine. 80

I will first describe in detail the mechanism employed for feeding the garment or other articles in proper relationship to the stamps to be applied and to the transfer mechanism, according to the present embodiment of the invention. This feeding mechanism as shown comprises an endless apron or belt b passing over rollers or drums b' , b'' arranged at front and rear of the machine. Said rollers may be provided with 90 short spurs or projections b^3 engaging the apron to prevent slipping between the apron and these rollers. The apron derives its movement, which in this case is intermittent, from a train of mechanism which comprises a link b^4 pivotally connected with a ratchet lever b^5 which carries a pawl b^6 in position to engage and intermittently actuate a ratchet wheel b^7 on the shaft b^8 which 95 shaft carries a spur gear b^9 meshing with a spur gear b^{10} on the shaft of the feed roll b^2 , the link b^4 being pivotally connected with a lever a^6 from which it derives its movement. In order to vary the throw of the ratchet a sector-shaped hood or shield b^{11} is adjustably mounted on the shaft b^8 , the adjustment being made by means of the slotted arm or extension b^{12} and the fastening screw b^{13} , so as to prevent the pawl from engaging the ratchet for as much as the arc of 100 movement of the ratchet as may be desired to give the necessary arc of rotation to the shaft b^8 . It will be understood that when the main lever a^6 descends the ratchet pawl 105

b⁶ is retracted and that when the lever *a⁶* rises the pawl *b⁶* causes a clockwise rotation, (Figs. 1 and 3) of the ratchet and its shaft *b⁸* and consequently a movement of the 5 apron *b* from right to left, the extent of which is dependent upon the arc of rotation imparted to said shaft *b⁸*.

I will now describe the details of mechanism for actuating the bed plate in cases 10 where it is desired to have the bed plate move. The bed plate *c* in this case is provided with a yielding cushion *c'* of felt or other yielding material and is supported on vertical slide rods *c²* which pass through 15 bearings *c³* formed on the sides of the frame of the machine. The reciprocating vertical movement is imparted by means of a link *c⁴* whose upper end is pivotally connected to the main lever *a⁶* and whose lower end is 20 connected with a lever *c⁵* which is secured to a rock shaft *c⁶*. To the rock shaft *c⁶* are arranged a pair of levers *c⁷* which are pivotally connected to the coöperating levers *c⁸*, which said levers *c⁸* are pivotally connected 25 with the bed plate *c*. The levers *c⁷*, *c⁸* form toggle levers the straightening of which by the rotation of the rock shaft *c⁶* serves to lift the bed plate into operative position beneath the belt or apron *b*, while the flexing 30 of these toggle levers by the reverse movement of the rock shaft *c⁶* serves to drop said bed plate to inoperative position. In order to adjust the traverse of the bed plate so as to accommodate it to articles of different thicknesses the rock shaft *c⁶* has its 35 opposite ends mounted in bearings formed in vertically adjustable slides or brackets *c¹²*, best shown in Fig. 7. These adjustable slides are of angular shape, the horizontal portion being passed through a slot *c¹⁴* in the rigid side frame, while the upward extension *c¹⁵* of the slide *c¹²* is provided with a slot to receive an adjusting screw *c¹⁶x* by which it is adjustably clamped when set to 40 the desired position. I prefer to provide a special adjusting means for positioning these slides *c¹²* which comprises a rock shaft *c¹⁶* carrying near its opposite ends lifting cams *c¹⁷* which lie directly beneath a downward inside extension or boss *c¹⁸* formed at 45 the lower inside portion of the slide *c¹²*, so that by the rocking of the shaft *c¹⁶* both slides *c¹²* are simultaneously raised and lowered to the proper position, the adjusting shaft *c¹⁶* being locked when properly set by means of a slotted plate *c²⁰* and a binding screw *c²¹*. The plate is formed with a handle *c²²* by which to conveniently rock the shaft *c¹⁶*. When the proper adjustment of 50 the fulcrum slides *c¹²* has been made as just described, the slides are firmly secured in position by means of set screw *c¹⁶*.

I will now describe the details of mechanism illustrated by which the upper presser member, which in this case is the heated

presser, is actuated. This presser member is shown in the form of a flat plate *d* which may be heated electrically or in any well known manner, and is supported by a vertical slide rod *d'* mounted in upper and lower bearings *d²* carried by a transversely adjustable frame *d³* (Fig. 2). This frame *d³* is made adjustable across the machine by mounting it upon a cross bar *d⁴* which passes through a pair of split hubs *d⁵* which are 70 formed on the frame *d³*. These split hubs are securely clamped upon the cross bar *d⁴* by means of set screws *d⁶* while the accidental turning or rotation on the bar *d⁴* is prevented by splining hubs or collars *d⁵* to 75 the cross bar. As shown in Fig. 3 a lifting collar *d⁷* is pinned to the slide rod *d'*, which said collar is provided on its front and rear faces with downward projections or ears *d⁸* which pass between the forks *d⁹* 80 of the forked lifting or actuating lever *d¹⁰*, which lever is secured to and actuated by the rock shaft *d¹¹*. The object of the downwardly projecting ears is to prevent any 85 rotative or torsional movement of the lifting rod *d'*. The rock shaft *d¹¹* by which the lifting and dropping of the presser *d* is controlled, is actuated by means of a lever *d¹²* secured thereon, which said lever *d¹²* is connected by means of the link *d¹³* with the 90 main lever *a⁶*, so that when the lever *a⁶* descends the rock shaft *d¹¹* rotates clockwise to allow the presser *d* to descend upon the belt into operative position, while the raising of the lever *a⁶* causes the presser *d* 100 through the intermediate mechanism to be lifted away from the feed belt and its co-operating presser member. It will be understood that the shaft *d¹¹* is mounted in arms or brackets *d¹⁴* projecting horizontally 105 from the fixed uprights *d¹⁵* of the machine frame. The forked lever *d¹⁰* is adjustable longitudinally of the shaft *d¹¹* by means of the clamping screw *d¹⁵*, which serves to clamp its split hub *d¹¹* securely to the shaft, 110 while permitting its adjustment along said rock shaft to conform to the transverse adjustment of the frame *d³*.

I will now describe the mechanism for feeding the tape which carries the transfer 115 stamps. The tape is wound in a coil or roll *e* upon an axis or rod *e'* which rests loosely around inclined brackets or arms *e²* projecting from the frame of the machine and is kept from moving downward on said brackets by means of the idler roll *e³*, which is carried in open bearings formed in said bracket *e²* in a position immediately below the tape roll so as to form a peripheral contact and support for said tape roll. The coöperating roll *e⁴* is mounted beneath the roll *e³* in fixed 120 bearings so as to form a support for the roll *e³*. As the tape or strip of transfer stamps is fed forward by the feeding means to be described it passes between the roll *e³* and 130

the presser tape roll e and also between the rolls e^3 and e^4 by which it is pinched. The uncoiling of the tape from the roll diminishes the diameter of the roll of tape, but as its supporting rod e' is free to slide down the inclined bracket e^2 the pressure of the tape roll will always rest against the delivery roll e^3 by reason of gravity. From the lowermost point of the roll e' the tape passes toward the rear of the machine directly above the travel apron b and in the path of the two reciprocating presser members c and d . To the rear of the plane of presser members is mounted a positively driven feed roll e^5 around which the tape passes and against which it is pressed by means of the coöperating idler roll e^6 whose journal boxes e^7 are spring pressed to give the proper pressure or pinch between these two rolls. The feed roll e^5 has on one end of its shaft a pinion e^8 meshing with the intermediate pinion e^9 which is driven by means of the large spur gear e^{10} whose shaft is rotated at a variable speed by means of the cone e^{11} and belt e^{10} and the coöperating cone e^{12} in the manner of the usual cone drive. The belt e^{10} is moved longitudinally of the cone pulleys by means of the shipper e^{13} which is adjustable transversely of the machine by means of the adjusting screw e^{14} and is held in position by the supporting rod e^{15} . The shaft of upper cone pulley e^{11} is rotated by means of the ratchet wheel e^{14} secured to one end thereof, which ratchet wheel is intermittently driven by means of an oscillating lever e^{16} upon which is mounted the pawl e^{17} . The ratchet arm e^{15} is actuated by means of a pivotal link e^{18} having adjustable connection with the rocking lever e^{19} which is secured to the rock shaft e^{20} carried by the adjustable frame d^3 . The rock shaft e^{20} is actuated by means of an arm or lever e^{21} which has a slot (Fig. 6) for receiving a pin e^{22} projecting from one side of the forked lever d^{10} , so that as the forked lever d^{10} is oscillated by the movement of this rock shaft d^{11} motion is imparted to the lever e^{20} by the slot and pin connection just described to oscillate the short rock shaft e^{20} . Hence it will be seen that both the tape feeding mechanism and the mechanism by which the upper presser is actuated derive their motion from and are controlled by the link d^{13} connected with the main lever a^6 . It will be understood, however, that while the descending movement of the lever a^6 serves to move the presser d into operative position, the pawl lever e^{16} is being retracted and is not actuating the ratchet which drives the tape feeding rolls; hence the tape is idling while the presser is descending and does not begin to feed until the presser lifts away from it. A hood e^{24} similar to the hood b^{11} may be employed both to regulate the arc of rotation of the ratchet wheel and to render the pawl inoperative during the first part of this forward or feeding movement, so that the presser d may be raised entirely clear from contact with the tape before the feeding movement of the tape begins. The tape is fed out of the machine after having left the feed rollers e^5 , e^6 by passing over an obliquely arranged guide bar or deflector e^{25} and between the draft rollers e^{26} , e^{27} the lower end of which is driven by the belt e^{28} from the pulley e^{29} carried by the shaft of the drum or roll b^2 .

It will be understood that the main lever a^6 is lifted positively by the cam but that the weight of the parts, particularly of the heavy presser d is sufficient to cause its descent though the descent may be accelerated by additional weight on the lever a^6 or otherwise. If the operator desires to arrest or prevent the movement of the transfer mechanism, this may be accomplished by swinging a pivoted latch f mounted on the end frame of the machine, into position beneath the outer end of the main lever a^6 . To facilitate this operation from either end of the machine, I provide a rock shaft f' extending from the front to the rear of the machine and provided at its ends with levers or handles f^2 , f^3 . The handle f^2 carries a link f^4 which engages the latch f so as to control its movement, as best shown in Fig. 2. The adjustable gage o consisting of a transverse bar mounted on adjustable supports o' serves as a guide in properly placing articles to be stamped on the feed apron.

What I claim is:

1. A machine for affixing transfer stamps embracing in its construction a heated presser or transfer member, means for presenting to the presser the fabric to be stamped and means for presenting in succession in proper relationship to the fabric and to the presser a plurality of transfer stamps, substantially as described.
2. A machine for affixing transfer stamps embracing in its construction transfer mechanism including a heated member and means for presenting to said transfer mechanism successively appropriate portions of the fabric to be stamped and the transfer stamps themselves in proper relation to each other, and actuating means for pressing the fabric and the stamp together.
3. In a machine for affixing transfer stamps the combination with a heated transfer mechanism of means for intermittently feeding the fabric to be stamped into position opposite the transfer mechanism and means for successively feeding a series of stamps to predetermined portions of the fabric, and means for actuating the transfer mechanism to press the fabric and the stamp together, substantially as described.

4. A stamp transferring machine embracing in its construction two opposed presser members, means for feeding the fabric to be stamped between said presser members, 5 stamp feeding mechanism for feeding the stamps successively into position against the fabric between the presser members, and means for moving one presser member against the other to press the interposed 10 stamp and portion of the fabric together, substantially as described.
5. In a stamp transferring machine the combination of the opposed presser members one of which is heated, an apron arranged to 15 travel between said presser members and convey the fabric to be stamped into proper relation thereto, means for positioning the stamps in succession upon portions of the fabric to be subjected to the presser, and 20 means for moving one presser member against the other in order to impress the stamp upon the fabric, substantially as described.
6. In a stamp transferring machine the 25 combination of the traveling apron for feeding the fabric to be stamped, the reciprocating heated presser movable toward and away from the apron, a continuous stamp-bearing tape and means for intermittently 30 feeding said tape in order to bring the stamps thereon successively against predetermined portions of the fabric as the fabric is fed into position opposite the heated presser, substantially as described.
7. In a stamp transferring machine the 35 combination of stamp feeding mechanism, mechanism for feeding the fabric, a presser member actuating mechanism therefor, a main driving shaft, a main actuating member controlling the tape feeding means, the 40 fabric feeding means and the presser mechanism and means for arresting said main actuating element in order to render the respective mechanism inoperative when desired, substantially as described.
8. In a stamp transferring machine the 45 combination of the intermittently movable apron, the intermittently reciprocated presser members, one of which is heated, the intermittently actuated tape feeding mechanism, the main actuating lever having suitable 50 connections with the tape feeding mechanism, the presser members and the apron to actuate the same in a predetermined order, substantially as described.
9. In a stamp transferring machine the 55 combination with the traveling apron adapted to receive and carry forward pieces of fabric to be stamped, a gage arranged 60 adjacent to said apron to form a guide for positioning the fabric on the apron, a tape roll support and feed mechanism for intermittently unwinding the tape from said roll

and feeding it above said apron, a heated presser and means for pressing the apron 65 the superimposed fabric and the tape on the heated presser, substantially as described.

10. In a transferring machine the combination with the opposed presser members, means including an apron for feeding the 70 fabric to be stamped and means for feeding the tape to be transferred between said presser members, actuating members for forcing said presser members together, said actuating members being adjustable in 75 order to vary their position with relation to the apron, substantially as described.

11. In a stamp transferring machine the combination of fabric feeding mechanism, stamp feeding mechanism and of opposed 80 presser members, one of which is heated, means for adjustably supporting said presser members, and the actuating mechanism for pressing one member against the other, said actuating mechanism being provided with adjustable connections to render 85 them operative in the different positions of adjustment to which presser members may be adjusted.

12. In a stamp transferring machine the 90 combination of a bed provided with a cushion surface, a heated presser, means for reciprocating said presser toward and away from said bed, an apron, means for causing said apron to travel intermittently between 95 the presser and the bed, feeding mechanism for feeding a stamp carrying tape between said presser and bed above the apron, said feeding mechanism being engaged with the mechanism of the reciprocating presser to 100 render the same inoperative when the presser rests upon the apron during the pressing and to cause the same to impart a step by step feed to the tape while the presser is in motion, substantially as de- 105 scribed.

13. A stamp transferring machine embracing in combination the automatically movable heated presser, a tape feeding mechanism, for intermittently feeding a 110 stamp carrying tape across the face of said presser, presser actuating mechanism, connections for coördinating the movement of said presser and of said tape feeding mechanism, and adjusting means by which the 115 feed of said tape may be varied without disturbing the relationship between the tape feeding mechanism and the presser, substantially as described.

In witness whereof, I have subscribed the 120 above specification.

CHARLES G. RICHARDSON.

In the presence of—

ANNIE BEATRICE BURKE,
